CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

DISTRIBUTING SYSTEM FOR ELECTRIC RAILWAYS.

1,295,886.

Specification of Letters Patent.

Patented Mar. 4, 1919.

Application filed June 5, 1916. Serial No. 101,732.

To all whom it may concern:

Be it known that I, CHARLES LE G. FORTESCUE, a subject of the King of Great Britain, and a resident of Pittsburgh, in the county 5 of Allegheny and State of Pennsylvania, have invented a new and useful Improvement in Distributing Systems for Electric Railways, of which the following is a specification.

10 My invention relates to electrical distributing systems and particularly to electric railway systems that employ alternating currents for propulsion purposes.

More particularly, my invention relates to 15 electric railway systems of the above indicated character which embody means for minimizing inductive disturbances that arise from the flow of propulsion currents and are impressed upon adjacent circuits, such as intelligence-transmission circuits, thereby interfering with their satisfactory operation.

Many systems have heretofore been proposed for minimizing the inductive disturbances impressed upon one electrical circuit by 25 another adjacent circuit but complete neutralization of the inductive effects has not been obtained in all cases. A particular system used in connection with electric railways which has given fairly good results embodies 30 the use of series transformers to inductively interlink the trolley conductor and the track circuit, whereby the return flow of the trolley currents may be confined to the track rails or to portions of the earth closely ad-

35 jacent to the track rails. In this manner, the zones of disturbing inducing influences arising from the return flow of the power currents are restricted and such currents are confined to limited regions close to the trolley conductor where their inductive effects

40 on an adjacent intelligence-transmission circuit minimize or neutralize, to some extent, the disturbances occasioned by the flow of the trolley currents. This system is fully 45 disclosed in U. S. Patent No. 1196300 issued to the Westinghouse Electric & Manufacturing Company, August 29, 1916, on an application filed by Charles F. Scott.

Another system proposed for interlinking 50 the trolley conductor and the track circuit in order to minimize the inductive disturbances occasioned by the flow of power currents in an electric railway system, is disclosed in a co-pending application of A. W. 55 Copley and Charles Le G. Fortescue, Serial

No. 66,733, filed December 14, 1915, and assigned to the Westinghouse Electric & Mfg. Company. This proposed railway system comprises a feeder conductor, a trolley conductor and a track circuit, the two former 60 conductors being so positioned with respect to an adjacent intelligence-transmission circuit, which is to be protected against inductive disturbances arising therefrom, that the resultant electromotive forces induced there- 65 in by reason of the current flowing in the trolley and feeder circuits shall be neutralized to such a degree as will not seriously interfere with the operation of the intelligence-transmission circuit. Moreover, the 70 trolley and feeder conductors are inductively interlinked, either with or without the track circuit, through transformers of a character similar to those employed in connection with the system disclosed in the above-mentioned 75 application of Charles F. Scott.

An object of my present invention is to provide an improvement in the systems disclosed in the aforementioned applications and particularly in that covered by application, Serial No. 66,733 in which disturbances arising from the flow of alternating currents in the distributing system and tending to interfere with the satisfactory operation of other circuits adjacent thereto, such as intelligence-transmission circuits, may be substantially neutralized in order to insure the satisfactory transmission of intelligence over the circuits subject to such disturbances. 85

To understand more fully the scope of my 90 present invention, reference may be had to the following description and the accompanying drawings in which Figure 1 is a diagrammatic view of a railway system embodying a form of my invention; Fig. 2 is 95 a simplified arrangement illustrating the system of Fig. 1; Fig. 3 is a diagrammatic view showing a substitute arrangement for the transformers employed in the systems of Figs. 1 and 2; Figs. 4, 5 and 6 are diagrammatic views of the character of Fig. 2 showing modified forms of the system of Fig. 1. 100

Referring to Figs. 1 and 2, a trolley conductor 1 supplies power to a railway system comprising a track circuit 2 that is divided 105 into a plurality of insulated sections 3 (one only of which is shown) employed for signaling purposes. This is a usual way of dividing the track circuit into a series of block sections each one of which may be pro- 110

tected by its own locally-controlled signaling device. A return feeder 4, paralleling the trolley conductor 1, provides means whereby the propulsion currents may return 5 to the source of power supply of the system which, in this instance, is represented as a single-phase alternator 5. One terminal of the alternator 5 is connected to the trolley conductor 1 and the other terminal is connected 10 to the return feeder 4, the full potential of the alternator 5 being impressed across the aforementioned conductors. At spaced intervals in the trolley conductor 1, are insulating joints 6, similar joints 6^a being correspondingly positioned in the return feeder 4. For convenience, the insulating joints 6 and 6^a may be placed at points corresponding to the position of insulating joints 7 in the track circuit 2, the latter being 15 provided in order that sections of the track circuit may be employed as local circuits or blocks for the electric signaling system. Associated with pairs of insulating joints 6 and 6^a are transformers 8 and 8^a, 20 the primary windings 9 and 9^a thereof being connected in series-circuit relationship with the trolley conductor 1 and in shunt to the insulating joints 6, and secondary windings 10 and 10^a being connected in 25 series-circuit relationship with the feeder conductor 4 and in shunt to the insulating joints 6^a. Two transformers 11 and 12 are associated with each division of the trolley and feeder conductors 1 and 4, one of said 30 transformers having windings 13 and 14, and the other having windings 15 and 16. The windings 13 and 14 and the windings 15 and 16 are interconnected with each other at common points 16^b and 16^a, respectively, 35 which points, in turn, are connected, through a conductor 17, to mid-points 18 on impedance bonds 19 that are inserted on both sides of the track-insulating joints 7. The impedance bonds 19 are of the usual form 40 of construction, such as are employed in electric railway systems equipped with electrical signaling devices of any usual form. When the signaling system comprises a plurality of insulated block sections, corresponding 45 terminals of the windings 13 and 15 of the transformers 11 and 12, respectively, are connected by means of conductors 20 and 21 to the terminals of the primary winding 9 of the series transformer 8, as shown 50 in the drawing. The other terminals of the windings 13 and 15 are connected to the windings 14 and 16, respectively, the free terminals of these latter windings being connected, by means of conductors 22 and 23, 55 to the terminals of the secondary winding 10 of the series transformer 8. A condensive reactance element 24 of proper value is connected directly across the terminals of the winding 9 and, similarly, a second condensive element 25 is connected across the ter-

minals of the secondary winding 10 of the series transformer 8.

An intelligence-transmission circuit 26, shown as a telephone circuit, is disposed in proximity to the trolley conductor 1 and the feeder 4, and is, therefore, subject to the inductive effects arising from the flow of propulsion currents in the railway system. For the satisfactory operation of the telephone circuit 26, it is essential that the inductive 75 disturbances impressed thereupon be minimized to a low degree, and, to this end, the distributing system of the present invention prevents the flow of induced currents of any appreciable value that may arise from the 80 flow of the propulsion currents in the railway system, as will be hereinafter disclosed.

It is evident that the electromotive forces induced in the disturbed circuit 26 are proportional to the currents flowing in the railway circuit, the extent of the disturbing zones and the proximity of the disturbed and disturbing circuits to each other. Therefore, by properly proportioning the currents flowing in the several directions in the distributing circuit, and by suitably placing the circuit conductors with respect to the telephone circuit, the electromotive forces induced in the telephone circuit will be substantially neutralized by inducing therein 95 equal and oppositely-directed electromotive forces under all conditions of load distribution on the railway system.

In Fig. 2, I have shown a simplified form of the system in Fig. 1 in which the transformer windings are more suitably arranged to facilitate in explaining their inter-relations. The telephone circuit 26 is assumed to be uniformly and equally spaced from the trolley conductor 1 and the return feeder 4. 100 The track circuit 2, in this instance, is held at a potential midway between the potential of the trolley conductor 1 and that of the feeder conductor 4 by means of the transformers 11 and 12, since the track circuit 2 110 is connected to the points 16^b and 16^a which represent common mid-points between the windings of the separate transformers. Accordingly, the ratio of the windings of each 115 of the transformers 11 and 12 is unity, the secondary windings 13 and 15 having induced therein electromotive forces equal to those impressed upon the windings 14 and 16, since the windings 15 and 16 and the windings 13 and 14 are mutually inductively 120 related, as mentioned above. Furthermore, the windings 9 and 10 of the series transformers 8 are mutually inductively related and, in this instance, comprise equal numbers of turns. The condensers 24 and 25 are selected 125 to have suitable capacities for supplying the magnetizing currents of the transformers 8 and 8^a. In other words, the impedance offered by the windings 9 and 10 of the series transformers 8 and 8^a to the flow 130

of the propulsion currents in the railway system is annulled or rendered negligible. This condition is maintained for currents having the frequency only of the propulsion currents. The signaling currents, for which the insulated track section 3 constitutes a local circuit, are afforded a very high impedance by the combination of the condensers 24, 25 and their associated inductive windings 9 and 10, and are, therefore, substantially precluded from flowing between adjacent track or block sections which is a very desirable condition since it lessens the danger of signaling devices indicating wrong traffic conditions.

To further illustrate the electrical conditions obtaining in the railway system of Fig. 2 at a certain instant, assume that a locomotive 26^a occupies the mid-position on the track section 3. The propulsion currents, which traverse the trolley and feeder circuit and which are represented by the full-line arrows 27, flow through the winding 9 of the transformer 8, along the trolley conductor 1 and a trolley pole 28 to the locomotive 26^a. At this point, the propulsion currents divide equally in two portions that flow along the track circuit 2 in opposite directions, since it is presumed that the track circuit 2 constitutes a uniform conductor and the train 26^a occupies a mid-position thereupon, as mentioned above. One-half of the propulsion current flows through the impedance bonds 19, the conductor 17, the winding 16 of the transformer 12, the conductor 23 and the secondary winding 10 of the transformer 8 to the return feeder 4. The other half of the propulsion current flows along the track circuit 2, the impedance bonds 19^b, the conductor 17^b, the winding 14^b of the transformer 11^b to the return feeder 4. It will be apparent, therefore, that the propulsion currents flowing in the trolley conductor 1 intermediate the generator 5 and the point A of the system is equal in value to, and opposite in direction from, that of the propulsion current flowing in the corresponding portion of the return feeder 4. Therefore, the inductive effects arising from the flow of the propulsion currents over this portion of the railway system are neutralized.

It becomes necessary, therefore, to neutralize the inductive effects arising from the flow of the propulsion currents in the portion of the railway system extending between the two groups of transformers. As mentioned above, one-half of the propulsion current flows through the winding 16 of the transformer 12. An equal and oppositely directed current is therefore induced in the winding 15 of the transformer 12, which induced current is represented, in direction, by the broken-line arrows 29. A local closed circuit, is consequently, established over which an induced current, equal to one-

half of the propulsion current, flows, and this local circuit comprises the winding 15 of the transformer 12, a section of the trolley conductor 1, the trolley pole 28, the train 26^a, a portion of the track circuit 2 and the impedance bond 19. Similarly, one-half of the propulsion current flows also through the winding 14^b of the transformer 11^b. In consequence thereof, current which is represented by the dot-and-dash arrows 30 and 75 is equal in value to the second portion of the propulsion current but flowing in an opposite direction thereto, is induced in a local closed circuit which comprises the winding 13^b of the transformer 11^b, the conductor 80 20^b, a section of the trolley conductor 1, the trolley pole 28, the train 26^a, a section of the rail circuit 2, the impedance bond 19^b and the conductor 17^b. Since the induced current flowing through the winding 13^b is 85 equal and opposite to the induced current flowing in the winding 15, the said currents, simultaneously traversing the trolley conductor 1, neutralize their separate inductive effects impressed upon the telephone conductor 26. Again, the inductive effects arising from the propulsion current flowing along the trolley conductor 1 to the trolley pole 28 are neutralized by the inductive effects arising from the flow of the portion of the propulsion current flowing along the section of the return feeder that is intermediate the two groups of transformers. Since, as previously assumed, the train 26^a occupies a mid-position on the track section 3, the corresponding section of the trolley conductor 1, over which the entire propulsion current flows, subtends a length of the telephone circuit 26 that is equal to one-half the length thereof subtended by the aforementioned portion of the return feeder 4 intermediate the two transformer groups, over which portion of the return feeder one-half of the propulsion current flows. The propulsion currents, in all instances, are offered zero impedance when flowing through the series transformers 8 and 8^a since the condensers 24 and 25 are so selected or tuned with the inductive reactance of the windings of the transformers as to annul the impedance of the windings 9 and 10 with which they are associated. As a result of the aforementioned distribution of the propulsion currents, the inductive disturbances impressed upon the telephone circuit 26 are substantially neutralized under all load conditions obtaining in the railway system.

In Fig. 3, the transformer 8 is shown as comprising a third winding 31 which is inductively related to both windings 9 and 10. 125 A condensive-reactance element 32 is connected in closed circuit with the winding 31 and, in this manner, means are provided for annulling the inductive characteristics of the windings 9 and 10 resulting from the flow of 130

the magnetizing currents therein. The structure shown in Fig. 3 is substantially an electrical equivalent of the transformer 8 of Fig. 1 in which the condensers 24 and 25 are 5 respectively connected in shunt to the windings 9 and 10.

Referring to Fig. 4, the windings 9 and 10 of the series transformers 8 are connected across the insulating joints 6 and 6^a in the 10 trolley conductor 1 and the return feeder 4, respectively, through resonating transformers 33. Each resonating transformer 33 comprises a primary winding 34 and a secondary winding 35, the latter being connected 15 in closed circuit with a condensive element 36. By the use of such an arrangement, a much smaller condensive element may be employed and the combined effect of the reactive element and such condensive 20 element is that of a comparatively large condenser. The condensive reactance of such a resonating transformer is so selected that it compensates for the inductive reactance of the transformer windings 15, 16, etc., 25 when alternating currents having the frequency of the propulsion currents traverse the several circuits described in detail in connection with the system of Fig. 2. In other words, the local circuits established by 30 the transformer windings 15 and 16 and the locomotive 26^a constitute series resonant circuits for alternating currents having the frequency of the propulsion currents. This condition is maintained irrespective of the 35 position of the locomotive 26^a on the track. The division of the propulsion currents between the several local circuits is consequently dependent only upon the ohmic resistance of the separate circuits, which resistance varies in value as the locomotive 40 traverses the system. This insures a correct division of the propulsion current, under all conditions of operation in the railway sections occupied by the locomotive and, 45 consequently, the inductive disturbances that may be impressed upon the telephone conductor 26 will be substantially neutralized, since the induced currents in the telephone circuit will, under all conditions, have 50 proper phase relationships. Of course, in selecting the condensers 36, the electrical characteristics of the locomotive 26^a must be ascertained in order to insure that the local circuits formed by the locomotive 26^a 55 will constitute series resonant circuits of suitable character.

In Fig. 5, the condensers 36 of Fig. 4 are connected intermediate the power transformer windings 15 and 16 and the windings 60 9 and 10 of the series transformer 8. In this position, the condensers 36 are subject to the currents flowing through the transformer windings 15 and 16 only. The condensers 36, however, are so chosen that the 65 local circuits established by the locomotive

26 will, in all instances, constitute series resonant circuits, as mentioned above.

In Fig. 6, the condensers 36 are connected intermediate the transformer windings 15 and 16 and the impedance bonds 19. In this 70 position, they act under all conditions as the condensers 36 of Fig. 5, the object also being, in this case, to provide series resonant circuits.

Of course, it will be understood that the 75 ratios between the transformer windings of the transformers 11 and 12 of Figs. 1 and 2 need not necessarily be unity, as has been assumed in the foregoing description. The potential of the track circuit 2 may be 80 other than the mid-potential between the trolley conductor 1 and the return conductor 4. In this instance, however, the spacing in the trolley conductor 1 and the return feeder 4, with respect to the telephone conductor 26, should be so adjusted and proportioned that the inductive effects impressed thereupon by reason of the flow of the propulsion currents may be substantially 85 neutralized. It will be presumed, however, that the currents flowing in the several local circuits will, in all cases, be substantially inversely proportional to the impedances of several circuits which, when properly tuned to the frequency of the propulsion currents, 90 constitute circuits having ohmic resistance only.

While I have shown and described several embodiments of my invention, it will be understood by those skilled in the art that 100 many modifications may be made therein without departing from the spirit and scope of the appended claims.

I claim as my invention:

1. An electric railway system comprising 105 a trolley conductor, a return feeder therefor, a track circuit, a transformer having its inducing and induced windings connected in series relationship between the trolley conductor and the feeder, inductively related windings for interlinking the trolley conductor and the feeder with each other, means for connecting an intermediate point of the said transformer windings to the track circuit, and condensive-reactance elements connected 110 in circuit to compensate for the inductive reactance of the windings of said transformer when alternating currents of a given frequency are impressed upon the system.

2. An electric railway system comprising 115 a trolley conductor, a return feeder therefor, a track circuit, means whereby the propulsion currents flowing from the track circuit to the return feeder may induce currents to flow in a local circuit comprising the trolley conductor and the track circuit, and additional means whereby said local circuit may 120 constitute a resonant series path for the flow of alternating currents of a certain predetermined frequency.

3. An electric railway system comprising a trolley conductor, a return feeder therefor, a track circuit, inductively related windings to interlink the feeder and the trolley conductor with each other, a plurality of transformers having inductively-related windings and connected in circuit on each side of said first inductively-related windings, the primary windings of said transformers being interconnected between the track circuit and the return feeder, and the secondary windings thereof being connected to the track circuit and the trolley conductor. 46
5. An electric railway system comprising a trolley conductor, a return feeder therefor, a track circuit, a plurality of spaced series transformers for inductively interlinking the trolley conductor and the feeder, and a transformer connected in circuit on each side of 55 said series transformers for interconnecting said trolley conductor, said return feeder and said track circuit with one another. 60
6. An electric railway system comprising a trolley conductor, a return feeder therefor, a track circuit, a plurality of spaced series transformers for inductively interlinking the trolley conductor and the feeder with each other, a transformer connected on each side of said series transformers having its primary winding connected between the track circuit and the feeder and its secondary winding connected between the track circuit and the trolley conductor, and condensive-reactance elements to compensate for the phase lag of the magnetizing currents supplied to said transformers. 65
7. An electric railway system comprising a trolley conductor, a return feeder therefor, a track circuit, series transformers inserted at spaced intervals for inductively interlinking the trolley conductor and the feeder with each other, a power transformer connected in circuit with the railway system positioned at each side of said series transformers, and condensive-reactance elements associated with said power transformers, whereby their inductive reactance may be completely compensated for when subjected to the flow of alternating currents having a predetermined frequency. 70
8. An electric railway system comprising a trolley conductor, a return feeder therefor, a track circuit, insulating joints inserted at corresponding points in the trolley conductor and the feeder, series transformers having their windings connected across said insulating joints to inductively interlink the trolley conductor and the feeder with each other, inductively related windings on both sides of said series transformers, said inductively-related windings being connected in series relationship across the trolley conductor and the feeder and having intermediate points thereof connected to said track circuit, and condensive-reactance elements 75 associated with said inductively related windings to compensate for their inductive reactance when impressed with alternating currents of a predetermined frequency. 80
- In testimony whereof, I have hereunto subscribed my name this 27th day of May, 1916. 85

CHARLES LE G. FORTESCUE.
